DRILL CLEANSING DEVICE

Ernest H. Dickenson, New York, N. Y., assignor to
 Ingersoll-Rand Company, Jersey City, N. J., a
 corporation of New Jersey

Application March 11, 1937, Serial No. 130,312

3 Claims. (Cl. 255—50)

This invention relates to cleansing devices, and more particularly to a cleansing device for removing detritus in a dry state, from a drill hole.

One object of the invention is to prevent the passage or expulsion of rock cuttings or dust to the atmosphere.

Another object is to eliminate the need of encumbering dust collecting devices adjacent the drill hole in order to maintain a clean working surface and to prevent the intermingling of dust with the atmosphere.

Other objects will be in part obvious and in part pointed out hereinafter.

In the drawing accompanying this specification and in which similar reference numerals refer to similar parts,

Figure 1 is a side elevation of a rock drill having the invention applied thereto,

Figure 2 is an elevation, in section, of a rock drill constructed in accordance with the practice of the invention,

Figure 3 is a transverse view taken through Figure 2 on the line 3—3, and

Figure 4 is an elevation, partly broken away, of a modified form of the invention.

Referring more particularly to the drawing, the invention is shown applied to a rock drilling mechanism 20 illustrated as being of the stoper type commonly used for drilling holes above the horizontal, as in the roof of a drift. The rock drill 20 accordingly comprises a percussive motor 21 and an extensible pressure actuated feeding motor 22, comprising a cylinder 18 and a piston 19, which supports and advances the percussive motor in a well understood manner. The feeding motor may be provided with a suitable throttle valve 17 for controlling the flow of pressure fluid into and from the cylinder 18.

The rock drill is further provided with a handle 23 which may be grasped by the operator to rotate the rock drill and thus also a reciprocable working implement 24 which the rock drill is intended to actuate.

The percussive motor 21, shown for illustrative purposes, comprises a cylinder 25 which may be suitably secured to a head 26 constituting also a head for the feeding motor and a support for the handle 23. Within the cylinder is a piston chamber 27 containing a reciprocating hammer piston 28, and in the wall of the cylinder 25 is a free exhaust port 29 which is controlled by the piston 28.

In the front end of the cylinder and in direct communication with the piston chamber 27 is an enlarged bore or recess 30 to accommodate an

anvil block 31 against which the blows of the hammer piston are delivered.

The periphery of the anvil block 31 may, as illustrated, be in slidable engagement with the wall of the recess 30, and on the front end of the anvil block is an extension 32 which extends slidably through a head 33 forming a closure for the front end of the cylinder. In the structure shown the portion of the extension 32 lying in the plane of the closure 33 is of polygonal shape and the bore in the closure 33 through which the extension extends is of corresponding shape so that the two will be suitably interlocked to prevent rotary movement of the anvil block with respect to the cylinder.

Secured to the free end of the extension 32, as by threaded engagement, is a sleeve or chuck 34 to receive slidably the shank 35 of the working implement 24, and arranged within the front end of the chuck 34 is a packing member 36 which bears against the surface of the working implement to prevent the entrance of abrasive material between the surfaces of the chuck 34 and the working implement.

The anvil block 31 also carries a rear extension 37 or stem 37 which extends slidably through the hammer piston 28 and through the head 26. The cooperating surfaces of the stem 37 and the head 26 are suitably sealed by a packing device 38, and leading from the free end of the stem 37 and through the anvil block 31 and the extension 32 is a passage 39 which, in the assembled and operative positions of the parts, registers with the passage 40 in the working implement 24.

The passages 39 and 40 may, if desired, be of the same cross sectional area so that cuttings entering the passage 40 may pass directly into and through the passage 39, it being understood that in the operative position of the parts the front end of the extension 32 will seat against the adjacent surface of the working implement to provide a direct path for the transmission of the blows of the hammer piston to the cutting end of the working implement. Thus the working implement and the anvil block and its extensions may serve as a conduit for conveying the cuttings from the drill hole.

Any suitable means, as for example a centrifugal pump 41 driven by a motor 16, may be employed for drawing the cuttings through the drilling mechanism. The pump is connected with the rear or free end of the stem 37 by a hose 42, and a separating device 43 may be interposed in the hose to effect the removal of solid matter from the air stream.

The distribution of pressure fluid to the piston chamber 27 is effected, in the present instance, by an oscillatory plate valve 44 arranged on the side of the cylinder 21. The valve 44 controls front and rear inlet passages 45 and 46, respectively, and is encased by a valve chest 47 into which the pressure fluid intended to be distributed is introduced by a conduit 48 threaded to the valve chest.

10 In the modified form of the invention illustrated in Figure 4 the drilling and feeding motors and, therefore, the anvil block and its extensions, are arranged coaxially with each other. In order, therefore, to enable the conduit 42 to be conveniently connected to the stem 37 and permit its free reciprocation with the anvil block the cylinder 18 of the feeding motor is provided with a hollow extension 49 which is connected to the head 26. In the side of the extension 49 is 15 an aperture 50 through which the conduit 42 may extend for connection with the stem 37.

20 In view of the foregoing description it is believed that the operation of the device will be obvious. It may be briefly stated, however, that when the drilling mechanism and the pump are 25 in operation the suction created by the latter will carry the detritus from the drill hole through the drilling mechanism and thereby prevent the dissemination of dust in the atmosphere.

30 I claim:

1. In a hole cleansing device, the combination of a reciprocable working implement having a bore extending entirely therethrough and a motor

having a reciprocatory hammer piston for actuating the working implement, means extending through the motor for transmitting the blows of the hammer piston to the working implement and having a bore to register with the first said bore, 5 and evacuating means attached to the first mentioned means for withdrawing cuttings from a drill hole through the bores.

2. In a hole cleansing device, the combination of a reciprocable working implement having an 10 axial passage extending entirely therethrough and a motor having a reciprocatory hammer piston, means in the motor for transmitting the blows of the hammer piston to the working implement having a passage to communicate with the interior 15 of the working implement, and evacuating means for withdrawing cutting from a drill hole through the working implement and the passage.

3. In a hole cleansing device, the combination 20 of a hollow reciprocable working implement and a motor having a reciprocating piston, means in the motor for transmitting the blows of the hammer piston to the working implement and having a passage to communicate with the interior 25 of the working implement, evacuating means connected to the rear end of the power transmitting means for withdrawing cuttings from a drill hole through the working implement and the passage, and chuck means for securing the first mentioned 30 means to the working implement.

ERNEST H. DICKENSON.
